LAST

Filed Aug. 22, 1923

Inventor:
Walter A. Krautler
by James R. Hodder
Atty.

UNITED STATES PATENT OFFICE.

WALTER A. KRENTLER, OF DETROIT, MICHIGAN, ASSIGNOR TO KRENTLER-ARNOLD HINGE LAST COMPANY, OF DETROIT, MICHIGAN, A CORPORATION OF MICHIGAN.

LAST.

Application filed August 22, 1923, Serial No. 658,806.

My present invention is an improved hinge last construction and the object is to simplify and perfect hinge lasts.

In my development of various methods of 5 lasts and hinge constructions, therefore, I have devised numerous simple and improved forms of hinge construction, such as that of my Patent No. 1,459,061, issued June 19, 1923 and my present invention is directed 10 primarily to improve the type of last shown in said patent, although the present invention, broadly considered, may be applied advantageously to other types of hinge or link construction.

15 In the manufacture of hinge lasts it is customary and desirable to have the fore part and heel part position arranged and equipped to swing on a pivot or pivotal axis permitting relative movement between the fore part and 20 heel part for straightening and collapsing the last. When a link connection is employed, as in my said prior patent, it is customary and desirable to position the link holding rivets or pins in fore part and heel part 25 aligned from the pivot or axis on which the two parts swing for relative movement. When the last is in lengthened or extended position these rivet points are below the pivot or axis and when the last is in shortened 30 or collapsed position these rivet points are above or at the opposite side of the pivot or axis. In order to have the connecting link members or hinge devices hold the last parts firmly and tightly in either collapsed 35 or extended position, it is necessary to permit a slight yield or "spring" as the last swings from one position to another, because the axis on which the connecting link or 40 hinge members swing is different from the pivot or axis on which the last members swing. In prior constructions where no provision was made for the difficulty above briefly outlined, the contacting wood faces of the last parts would wear quickly to permit 45 this swinging action and therefore when the last was in either extended or collapsed position the link and hinge devices were loosened because of the strain and wear involved in "snapping" or "springing" the last 50 parts past the center axis. In my present invention I have provided automatic means which will admit of a slight lengthening of the hinge or link members relatively with the hinge or pins uniting the same to fore part 55 and heel part as the last swings by the piv-

otal center or axis on which the last parts swing. This slight lengthening or yield is furthermore automatically actuated to hold the last parts in as close and tight end contact in either collapsed or lengthened position as when the last is being swung by the pivotal axis, and thus prevents undue wear upon the contacting wood faces of the last parts, compensating, therefore, as well as preventing the looseness between the last parts during use.

Thus my present invention enables the hinge members and the last members to swing on disaligned pivots or axes with automatic means to compensate for the varying 70 tension involved and furthermore to automatically replace the hinge or link retaining action after each movement.

I accomplish this desirable feature by providing the link and one connecting rivet or 75 pin,—with a bevelled face permitting the pin and link to move slightly along said bevelled face, thus allowing effective lengthening of the link and pin. In embodying the present invention in a link and spring 80 type of last shown in my said Patent No. 1,459,061, I form one end of the link or hinge member with an inclined or bevelled face along which the adjacent pivot can "ride" 85 or move when the last parts are snapped or sprung by the center or axis of movement of the two parts of the last.

Referring to the drawings illustrating a preferred embodiment of the invention—

Fig. 1 is a side view of a last partly in 90 cross section and in lengthened position.

Fig. 2 is a similar view illustrating the last partly flexed.

Fig. 3 is a fragmentary view illustrating the last in completely collapsed position.

Fig. 4 is a cross-sectional view through the pivotal center of the last parts.

Fig. 5 is a view of a modified form of link.

As shown in the drawings Fig. 1 indicates 100 the forepart and Fig. 2 the heel part of a last which may be of any size, type, style and with dividing lines of cut, if desired. As herein illustrated a well-known type of "knuckle joint" last is shown, having a concave face 3 formed on the forepart and the corresponding convex or knuckle portion 4 on the heel part. In the fore part 1 is also formed a recess 5 and in the heel part a similar recess 6 of sufficient width and depth to 110

receive the connecting hinge 10 and one or more springs 12. The link 10 is firmly held to the fore part 1 by a pin 15 and is adjustably secured in the heel part at the pin 16 and 5 around these pins the springs 12 are clamped, thus exerting a constant tightening tension on the last parts. The lines of cut on the last here shown provide top faces 17 and 18, permitting a substantial opening of 10 the last and bottom shoulders 19 and 20, constituting abutments or contacting portions when the last is closed.

In the form of last as herein illustrated, I prefer to position a central or pivotal pin 21 15 on which the fore part 1 and heel part 2 swing for their relative movement. Such a pin, however, is not necessary to the features of my present invention since any construction permitting a relative pivotal movement 20 of the heel part and fore part, either on a positive pivotal pin such as 21,—or on an imaginary line or axis—so long as this axis is disaligned with the axis on which the link or hinge member 10 swings—either 15 or 16 25 in the present form—will carry out my invention.

Where a pivotal member 21 is employed and a single link 10, I form a slot 22 in the link of substantially greater width than the 30 diameter of the pin 21, as well as of sufficient length for the flexing of the last parts without the pin 21 striking the link 10. Assuming that the link 10 will swing on the fore part and hence on the rivet 15 I provide at 35 the heel part portion of the link—that adapted to engage the rivet 16—a bevelled face 25 which will permit relative movement of the rivet 16 and this end portion of the link 10 to allow for a lengthening of the heel 40 and fore part connections on the link while the last is being moved from collapsed to lengthened position around the pivot on axis 21 and yet at all times keeping the last parts in rigid union. This position is illustrated 45 in Fig. 2. When the last is in collapsed position no excessive strain is put thereon and the springs 12 hold the two parts in collapsed position because the rivets 15 and 16 are beyond or above the center. When the last 50 is in collapsed position the faces 19 and 20 are in firm engagement and the strain incident to shoe making, levelling machine operations, etc., will tend to hold the link 10 with the rivet 16 at the base of the bevelled 55 face 25. I may form this bevelled face 25 either as an open recess, as illustrated, or as a slot in the link 10 as indicated in the dotted lines in Fig. 2 and by the numeral 30 in Fig. 5. In either event the feature of having the link 10 swing on the axis with provision for lengthening movement and the last parts 1 and 2 swing on a disaligned axis and yet keeping both last parts and link 60 in firm and rigid union while permitting 65 the free flexing of the last without undue

wear and substantially under the same tension, is carried out.

My invention is further described and defined in the form of claims, as follows:

1. A two-part last having said parts constructed and arranged for relative movement about a pre-determined axis, means connecting said parts movable on a different axis and means formed on said last named means acting automatically to permit the movement of said last parts and connecting means on the different axes at substantially uniform tension. 70

2. A last having a heel part and a fore part arranged for relative movement about a pre-determined axis, a connecting link uniting said parts at points remote from said axis and means formed integral with the connecting link and connecting one end of said link with one of the last parts to permit of an effective lengthening and shortening of said link during collapsing and straightening of the last. 80 85

3. A last having a heel part and a fore part arranged for relative movement about a pre-determined axis, a connecting link uniting said parts at points remote from said axis and means formed integral with the connecting link and connecting one end of said link with one of the last parts to permit of an effective lengthening and shortening of the last in combination with spring tension means uniting the last parts. 90 95

4. A hinge last having a fore part and heel part arranged for relative pivotal movement, a connecting link united to said parts by fixed rigid rivets, one of said link and rivet portions being constantly in operative engagement while permitting an effective lengthening and shortening of the effective link joining action during flexing of the last parts. 100 105

5. A two-part last arranged for relative movement, retaining pins, a pivot pin on which said last parts move, a rigid link operatively connected to said retaining pins uniting said last parts and having one end formed with an inclined face permitting the link to move relatively on the adjacent retaining pin to allow an effective lengthening 110 115 of the same during flexing of last.

6. A two-part last arranged for relative movement, retaining pins, a pivot pin on which said last parts move, a rigid link operatively connected to said retaining pins uniting said last parts and having one end formed with an inclined face permitting the link to move relatively on the adjacent retaining pin to allow an effective lengthening 120 125 of the same during flexing of last in combination with spring tension means holding the last parts in yielding position.

In testimony whereof, I have signed my name to this specification.

WALTER A. KRENTLER.
